HENRY A. FANSHAWE, OF NEW YORK, N. Y.

Design No. 3,447, dated April 13, 1869.

DESIGN FOR A TRADE-MARK

The Schedule referred to in these Letters Patent and making part of the same.

To all whom it may concern:

Be it known that I, HENRY A. FANSHAWE, of the city and State of New York, have originated a Design for a Trade-Mark, of which the following is a full, clear, and exact description, reference being had to the accompanying drawings, making a part of this specification, and which represents the following device:

A shield, surmounted by a crown and goat's head, and surrounded by ornamental scroll-work.

The field of the shield is barred, the left half with perpendicular parallel bars, the right half with horizontal parallel bars.

On each side are diagonal cross-bars, forming an angle at the centre, and bearing three fleur de lis.

Above these cross-bars are two small lions, one on either side, and, beneath the cross-bar, a larger lion.

Detached from the shield, and disposed in any convenient position near to it, is the motto, "Semper Idem," and beneath the shield, is a wreath of leaves.

What I claim as my invention, and desire to secure by Letters Patent, is—

The design and motto for a trade-mark, herein set forth.

HENRY A. FANSHAWE.
